UNITED STATES PATENT OFFICE

2,257,583

CHAIR

Glenn D. Wood, Elkhart, Ind., assignor to Posture Research Corporation, Elkhart, Ind., a corporation of Indiana

Application November 9, 1939, Serial No. 303,594

3 Claims. (Cl. 155—116)

This invention relates to improvements in chairs and it consists of the matters hereinafter described and more particularly pointed out in the appended claims.

The chair with which the present invention is more especially concerned is of the so-called "easy" or "lounging" type, used in homes and some times in offices and wherein the seat which is independent of the pivoted back rest, is capable of a forward and backward movement on the base. Heretofore in chairs of this kind, the seat moved in opposition to the back rest. That is, it moved forward and backward when the back rest moved backward and forward.

With such a chair, certain objections are present. For instance, when the occupant leaned back against the back rest to change occupant's position against a cushioning action, the seat moved forward and carried the buttocks forward and this caused the body of the occupant to slump. Such a slump leaves the lumbar regions of the body unsupported so that an unnatural posture is induced in the body which not only cramp and retard the action of certain body organs, but also strains and tires the back. Also, such a relative movement between the back rest and seat causes a drawing up and a wrinkling of the clothing which in turn produces an unkempt appearance for the occupant.

One of the objects of the present invention is to provide a chair of this kind which overcomes the objections heretofore present in chairs of the so-called "easy" or "lounging" type.

Another object of the invention is to provide a chair of this kind wherein the seat slides backward and forward with the backward and forward swinging movement of the back rest.

A further object of the invention is to provide a chair of this kind which is of simple construction for low cost production and which requires no manipulation of any part of the chair by the occupant when seated therein to change the position of the seat and back rest.

Again, it is an object of the invention to provide a chair of this kind which is upholstered to harmonize with similar furniture in a home or office, with no parts visible to indicate the movable character of its seat and back rest.

The above mentioned objects of the invention as well as others, together with the advantages thereof will more fully appear as the specification proceeds.

In the drawing:

Fig. 1 is a vertical sectional view through a

chair, from front to back, embodying the preferred form of the invention.

Fig. 2 is a vertical sectional view through one side of the chair as taken on the line 2—2 of Fig. 1.

Fig. 3 is a longitudinal sectional view through a certain cushioning brace embodied in the chair and which will be more fully referred to later.

Referring now in detail to that embodiment 10 of the invention illustrated in the drawing, the chair includes a base 5, a seat 6 and a back rest 7. The base includes front, rear nad side members 8—9 and 10 respectively and at each side of the chair the base supports an upright hollow side arm 11 that extends into an elevation well above the seat. The hollow side arms, which may or may not be upholstered, are each connected to the associated side member of the base by a spacer 12, as appears in Fig. 2. Along the 15 inner surface of the top margin of each side member 10 of the base is a side rail 13.

The seat includes a frame that is shorter from front to rear than the base and has side members 14—14 and a rear end rail 15 and suitable 25 padding and upholstery 16. The side rails 14 of the seat are so spaced apart laterally, as to be disposed in substantially the vertical planes of the side rails 13 of the base. The rear end member 15 of the seat is normally located in a 20 vertical plane forward of that of the rear member 9 of the base, while the front end of the seat is normally disposed in the vertical plane of the front member 8 of the base.

In the bottom portion of each side member 30 35 14 of the seat, toward the front and rear ends of the seat, are located recesses 17—17, each of which receives an antifriction roller 18 having a peripheral rolling engagement on a track 19 provided therefor on each rail 13. Rollers 18 40 on opposite sides of the seat frame are connected together by a shaft 20. With the structure described, it is apparent that the seat is capable of a straight line, horizontal forward and backward movement on the tracks 19 carried by rails 13. To hold the seat down upon the rails and 45 at the same time permit the forward and backward movement above mentioned, a spring 21 is located at each side of the seat. Each spring is fixed at one end to the inner face of a side member 14 of the seat and is fixed at the other end to a pin 21a projecting inwardly from the associated side member 10 of the base.

The back rest 7, which is suitably upholstered, is provided in its forward bottom portion with a recess 22 which appears in Fig. 1. A shaft 23

extends laterally through the said recess and the ends of said bottom portion of the back rest and where it is operatively secured to the back rest as a whole and this shaft is suitably journaled at its ends in both side arms 11—11. A pair of arms 24 is fixed in spaced relation on the shaft 23, in the recess 22. One end of a link 25 is pivotally connected to each arm 24 and the other end of said link is pivotally connected to the back member 15 of the seat frame.

Between each side of the back rest 7 and the side arms 11—11, is located a device indicated as a whole as at 26 and which devices function to cushion the rearward swinging movement of the back rest and to return the same forwardly. Said cushioning devices may be of the kind shown in the Wood Patent 2,018,825 of October 29, 1935. As shown in Fig. 3, each device comprises a tube 27 closed at one end and there pivotally connected to the side of the back rest as indicated in Fig. 1, and in the other end of said tube is a tubular bushing 28. A rod 29 slides through this bushing and its outer end is pivotally connected to a side member 11 of the base as appears in Figs. 1 and 2. A nut 30 is threaded on that end of the rod within the tube and a helical spring 31 in said tube surrounds the rod between said nut and bushing 28.

In the use of the chair, the back of the occupant is engaged against the back rest and the buttocks are engaged upon the seat. When the occupant leans backward, against the back rest the latter swings or rocks rearwardly by reason of the shaft 23 turning or rocking, counterclockwise as appears in Fig. 1, in its end bearings. This action is cushioned by the reason of the compression of the springs 31 in the devices 26. As the shaft 23 so rocks, the seat 6 is caused to slide or move rearwardly on the tracks 19, by reason of the arms 24 and links 25. When the pressure of the occupant leaning against the back rest is eased off, the springs 31 in the cushion devices 26 expand and pull or return the back rest forwardly. By reason of the arm and link connection between the seat and the shaft 23, the seat is slid forwardly to the position limited by the cushioning devices and which position is the normal position of the seat when occupied.

With the seat moving backward and forward, in synchronism with the backward and forward movement of the back rest instead of moving in opposition thereto as in most of the so-called "easy" chairs, several advantages are present. While there is a change in the angular position between the torso and the legs of the occupant in the use of the chair, there is no sliding action between these body parts and parts of the chair they engage. Therefore, there is no such movement as will wrinkle the clothing or will cause the occupant to assume a slumped position with the resulting cramping of the internal organs of the body. The chair is indeed comfortable to occupy because the body muscles are relaxed instead of tensed as in a chair wherein the seat moves in opposition to the back.

The improved chair permits the occupant to

assume a somewhat reclining position and as the seat moves "with" the back rest instead of "against" the back rest, the back rest adjusts itself to the position desired by the occupant and stays in that position.

While in describing the invention I have referred in detail to that embodiment of the invention illustrated in the drawing, the same is to be considered only in the illustrative sense so that I do not wish to be limited thereto except as may be specifically set forth in the appended claims.

I claim as my invention:

1. A chair embodying therein a supporting base, means providing a seat mounted on the base for a backward and a forward rolling movement, means providing a back rest, a shaft carried by said back rest means and journaled at its ends in parts stationary with the base and whereby said back rest means is capable of a backward and a forward rocking movement, means operatively connecting the base and said back rest means for cushioning the backward swinging movement thereof and for imparting a forward return movement thereto, and means operatively connecting said shaft and said seat comprising a crank on the shaft and a pivoted link on the seat pivotally connected together for effecting a backward and forward rectilinear movement of the seat in the same direction simultaneously with the back rest.

2. A chair embodying therein a base, a seat mounted on said base for a backward and a forward movement, a back rest, a shaft carried by said back rest near the lower end of the back rest and journaled at its ends in parts stationary with said base and whereby said back rest is capable of a backward and a forward rocking movement, means connecting said base and said back rest for cushioning the backward movement thereof and for causing the forward return movement thereof, an arm carried by said shaft, and a link connecting said arm and said seat for causing a backward and a forward rectilinear movement of said seat with the backward and forward movement of the back rest.

3. A chair embodying therein a supporting base, a seat mounted on the base for a straight line backward and forward movement, a back rest in contact with the seat, a shaft carried by the back rest and having its ends journaled in parts stationary with the base whereby said back rest is capable of a backward and forward rocking movement, a crank on the shaft, a link pivotally mounted on the seat at one end and pivotally secured at its other end to the crank, whereby upon rocking movement of the back rest rearwardly the seat will be moved rearwardly and in contact with the back rest and upon rocking movement of the back rest forwardly the seat will be moved forwardly and in contact with the back rest and resilient means secured to the base and to the back rest for restoring the parts to normal position.

GLENN D. WOOD.
